DESIGN FOR A CLOTHES WRINGER FOR A WASHING MACHINE

Kent C. Haven, Syracuse, N. Y., assignor to Easy
Washing Machine Corporation, Syracuse, N. Y.,
a corporation of Delaware

Application June 18, 1937, Serial No. 69,892

Term of patent 14 years

To all whom it may concern:

Be it known that I, Kent C. Haven, a citizen of the United States of America, residing in the city of Syracuse, county of Onondaga, and State of New York, have invented a new, original, and ornamental Design for a Clothes Wringer for a Washing Machine, of which the following is a specification, reference being had to the accompanying drawing forming part thereof.

Figure 1 is a perspective view showing one side and one end of the clothes wringer of my new design.

Figure 2 is a perspective view showing the same side and the other end of the clothes wringer of my new design.

The opposite side of the clothes wringer is substantially the same in appearance as the side shown.

I claim:

The ornamental design for a clothes wringer for a washing machine, substantially as shown and described.

KENT C. HAVEN.
